(57) **CLAIM**

The ornamental design for a set-screw holder, as shown and described.

DESCRIPTION

FIG. 1 is a perspective view of a set-screw holder;
FIG. 2 is a bottom perspective view of the set-screw holder;
FIG. 3 is a front view of the set-screw holder;
FIG. 4 is a rear view of the set-screw holder;
FIG. 5 is a top view of the set-screw holder;
FIG. 6 is a bottom view of the set-screw holder;
FIG. 7 is a left side view of the set-screw holder; and,
FIG. 8 is a right side view of the set-screw holder.
The broken lines in the figures depict portions of the set-screw holder and form no part of the claimed design.
